COMBINATION POCKETBOOK AND
CARD CASE

Henry M. Herbener, Thomasville, Ga.

Application October 25, 1945, Serial No. 624,347

13 Claims. (Cl. 150—35)

1

My invention relates to a folder, card case or pocket construction.

An important object of the invention is to provide a device of the above mentioned character having rounded edges and all stitching covered from exterior view.

A further object of the invention is to provide a device of the above mentioned character having a partition element to which the inwardly folded marginal tongues are secured, producing rounded edges and a bellows construction.

A further object of the invention is to provide a two-layer partition element, which is stitched inwardly of its marginal edges, and having the marginal tongues secured thereto, providing a bellows construction and limiting the spreading action of the sides of the partition element.

A further object of the invention is to provide a two-layer partition element stitched in a manner for forming locking tongue receiving openings between the layers.

A further object of the invention is to provide means whereby parts may be sewed together where the maximum strains occur and connected by interlocking tongues, where the strains are at the minimum.

A further object of the invention is to provide a device of the above mentioned character wherein the outer main side, lining and window side may be stitched together, forming a marginal tongue portion which is folded in between a two-layer partition element.

A further object of the invention is to stitch the two-layer partition element to the tongues of the outer main side, providing openings between the two layers for receiving the locking tongues of the window side.

Other objects and advantages of the invention will be apparent during the course of the following description.

In the accompanying drawings forming a part of this application and in which like numerals are employed to designate like parts throughout the same,

Figure 1 is an exploded perspective view of the several blanks employed in forming the folder, card case or pocket construction,

Figure 2 is a perspective view of the outer blank, showing the longitudinal tongues folded inwardly and sewed to one side of the two-layer partition element,

Figure 3 is a transverse section taken on line 3—3 of Figure 2,

Figure 4 is a perspective view of the parts shown in Figures 2 and 3, with the upper layer of the

2

partition element folded over and provided with a U-shaped line of stitching.

Figure 5 is a transverse section taken on line 5—5 of Figure 4,

Figure 6 is a longitudinal section taken on line 6—6 of Figure 4,

Figure 7 is a view similar to Figure 4, showing the next step of arranging the previously stitched companion two-layer partition element upon the upper side of the outer blank,

Figure 8 is a longitudinal section taken on line 8—8 of Figure 7,

Figure 9 is a view similar to Figure 7, showing the next step of arranging the window sides upon the partition elements,

Figure 10 is a longitudinal section taken on line 10—10 of Figure 9,

Figure 11 is a perspective view, open, of the completed device,

Figure 12 is a longitudinal section taken on line 12—12 of Figure 11,

Figure 13 is a transverse section taken on line 13—13 of Figure 11,

Figure 14 is a transverse section taken on line 14—14 of Figure 11,

Figure 15 is a perspective view of the device, closed,

Figure 15' is an exploded perspective view of the several blanks for forming a modified form of folder, card case or pocket construction,

Figure 16 is a perspective view showing the assembled main outer sides and lining,

Figure 17 is a transverse section taken on line 17—17 of Figure 16,

Figure 18 is a perspective view of the assembled main outer sides and lining and the inner or window sides positioned flat beneath the main outer sides, parts being stitched together,

Figure 19 is a longitudinal section taken on line 19—19 of Figure 18,

Figure 20 is a perspective view similar to Figure 18, showing the folded partition units placed in position upon the lining,

Figure 21 is a longitudinal section taken on line 21—21 of Figure 20,

Figure 22 is a perspective view like Figure 20, showing the step of folding the tongues of the main outer side inwardly between the sides of the partition units and showing the next stitching step,

Figure 23 is a transverse section taken on line 23—23 of Figure 22,

Figure 24 is a perspective view like Figure 22, but showing the next step of swinging the inner or window side upwardly over the partition units

and passing connected tongues between the ends of the sides of the partition units,

Figure 25 is a longitudinal section taken on line 25—25 of Figure 24,

Figure 26 is a transverse section taken on line 26—26 of Figure 24,

Figure 27 is a perspective view similar to Figure 24, showing the next step of folding the folding tongues of the window sides between the marginal edges of the partition units and passing the locking tongues through the passages of the lines of stitching of the partition units, and,

Figure 28 is a transverse section taken on line 28—28 of Figure 27.

The folder, card case or pocket construction includes an outer blank 30, formed of flexible material. This blank comprises first and second main outer sides 31 and 32, foldable upon transverse lines 33 and connected by an intermediate strip 34. The first main outer side 31 is provided with longitudinal folding tongues 35, foldable upon lines 36. The first side is also provided with a transverse folding tongue 37, foldable upon a transverse line 38. The ends of these folding tongues are beveled and a tapered tab 39 is formed upon the first side 31 at the outer corners, between these beveled ends, and these tabs are adapted to be folded inwardly to afford blunt turned edge corners. These tabs 39 may be first folded inwardly and secured to the front side by cement or the like. The second main outer side 32 is provided with longitudinal folding tongues 40 and these folding tongues carry longitudinal locking tongues 41. The second side 32 is provided at its outer end with a transverse folding tongue 42, foldable inwardly upon a transverse line 43, and this transverse folding tongue carries locking tongues 44, as shown. Tapered tabs 45 are formed upon the outer corners of the second side 32 and are foldable inwardly over this side to provide blunt turned edge corners. The tabs 45 may be first folded inwardly and secured to the side 32 by cement or the like.

The numeral 46 designates a two-layer partition element blank, comprising a first side 47 and a second side 48, foldable upon a transverse line 49.

The first side 47 is now arranged upon the first side 31 and the longitudinal folding tongues 35 are folded inwardly over the first side 47, and elements 35 and 47 are secured together by lines of stitching 50, passing through these elements and not through the first side 31, Figures 2 and 3. Both lines of stitching 50 may be effected by a tubular stitching machine or one folding tongue 35 may be stitched flat to the first side 47, which is then folded over and stitched to the companion folding tongue 35 by a tubular stitch sewing machine. When the first side 47 is thus secured to the longitudinal folding tongues 35, the second side 48 may be flat and arranged above the second side 32, as shown in Figure 2. The next step is to fold the second side 48 upon the transverse folding line 49 so that it overlaps the first side 47 and this produces a two-layer partition element, having an inner folded edge at the line 49, Figure 4. The two sides or layers 47 and 48 are now secured together by a U-shaped line of stitching 52, Figures 4 and 5, passing through the sides 47 and 48 only, and not through the first side 31. This U-shaped line of stitching is spaced inwardly a suitable distance from the marginal edges of the sides 47 and 48, providing flexible marginal strips or portions 53 and 54,

which aid in producing a bellows construction. The U-shaped stitching 52 prevents the sides 47 and 48 spreading inwardly of the line of stitching.

The numeral 55, Figure 1, designates a companion two-layer partition element blank, similar to the blank 46 and including a first side 56 and a second side 57, foldable upon each other upon a transverse line 58. These sides are brought to the folded position and are stitched together by a U-shaped line of stitching 59, passing through the same only, and this is done before the partition element is arranged in the assembled position. The lines of stitching 59 are stopped or interrupted adjacent to the longitudinal edges of the sides 55 and 56, affording openings or passages 60 between the sides 56 and 57. The line of stitching 59 is further stopped or interrupted adjacent to the transverse edges of the sides 56 and 57, for forming openings or passages 61, between the sides 56 and 57. The line of stitching 59 is spaced inwardly from the edges of the sides 56 and 57 for providing marginal edge portions 62 and 63, aiding in forming the bellows construction. The line of stitching 59 prevents the separation of the sides 56 and 57 inwardly of this line of stitching.

The next step in assembling is to arrange the folded sides 56 and 57 upon the first main outer side 32, Figures 7 and 8.

The numeral 64 designates a window blank or side having an opening covered by a transparent sheet 65, formed of Celluloid or the like and secured in place by a line of stitching 66 or other suitable means. Formed upon the window side 64 are longitudinal folding tongues 67, foldable upon longitudinal lines 68. Formed upon the window blank 64 is a transverse folding tongue 69, foldable upon a transverse line 70. Folding tongues 67 and 69 have their ends beveled and the window side 64 is provided at its corners with tapered tabs 71, foldable inwardly to provide blunt turned edge corners, and preferably first secured to the side 64 by cement or the like.

The numeral 72 designates a companion window blank or side, having an opening covered by a sheet of transparent material 73, secured thereto by a line of stitching 74 or the like. The window side 72 has longitudinal folding tongues 75, foldable upon longitudinal lines 76. The folding tongues 75 carry locking tongues 77. The window side 72 has a transverse folding tongue 78, foldable upon a transverse line 79, and the transverse folding tongue 78 has locking tongues 80. The side 72 is provided at its corners with tapered tabs 72', foldable over the inner face of the side 72 to provide blunt turned edge corners. The tabs 72' are preferably first folded over the side 72 and secured thereto by cement or the like.

The next step in assembling the parts is to arrange the window side 64 upon the two-layer partition element 46 and the window side 72 upon the two-layer partition element 55, Figures 9 and 10. The inner edge of the window side 64 is adjacent to the folded edge 49 of the two-layer partition element 46 and the inner edge of the window side 72 is adjacent to the folded edge 58 of partition element 55. The folding tongues now extend outwardly and are generally horizontal. The longitudinal folding tongues 67 of the window side 64 are now folded inwardly between the sides 47 and 48 of the partition element 46 and are secured to the upper side 48 by cement or the like. The transverse folding tongue 37 of

the main outer side 31 and the transverse tongue 69 of the window side 64 are now folded inwardly and are arranged between the sides 47 and 48 of the partition unit 46. The tongue 37 is secured to the side 47 by cement or the like, while the tongue 69 is secured to the side 48 by cement or the like. This completes one pocket unit. The longitudinal tongues 40 of the main outer side 32 are now folded inwardly and are arranged between the sides 56 and 57 of the two-layer partition unit 55 and the locking tongues are passed through the openings 60 and engage behind the line of stitching 59. The folding tongues 75 of the window side 72 are folded inwardly and are arranged between the sides 56 and 57 of the partition unit 55 and the locking tongues 77 are passed through the openings 60 and engage behind the line of stitching 59. The transverse folding tongue 42 of the main outer side 32 is folded inwardly and is arranged between the sides 56 and 57 of the partition unit 55 and its locking tongues 44 are passed through the openings 61 and engage behind the line of stitching 59. The transverse folding tongues 78 of the window side 72 are folded inwardly and are arranged between the sides 56 and 57 and the locking tongues 80 are passed through the openings 61 and engage behind the line of stitching 59. This completes the second pocket unit. The several corner tabs are ordinarily folded in and secured in place prior to this point of assembly, but if desired, they may remain in the open position up to this point, and may be folded in and cemented to their corresponding sides, at this point of assembly.

The partition units form with the main sides main pockets 81, and the window sides form with the partition units pockets 82. By virtue of the several folding tongues and two-layer partitions, a folder is provided including units, each unit having a bellows construction at its marginal edges. The bellows construction affords rounded marginal edges and all stitching is concealed from exterior view. The several pockets are closed at their outer ends and open at their inner ends and the pockets extend throughout the entire length and width of their sides, thus providing the maximum holding space. The completed folder is shown open in Figure 11, whereby access may be had to the open inner ends of the pockets. In Figure 15, the folder is shown closed. As shown in Figure 15, the marginal edges of all pockets are folded, and all stitching is concealed from exterior view.

In Figures 15' to 28, I have shown a further modification of the invention. In these figures, the numeral 83 designates a main outer blank, having main outer sides 84, foldable upon transverse lines 85, providing an intermediate connecting strip 86. At the ends of the connecting strip 86, attaching tongues 86' are provided, foldable upon longitudinal lines 87. The main outer sides 84 have longitudinal folding tongues 88, foldable upon longitudinal lines 89. These sides also have transverse folding tongues 90, foldable upon transverse lines 91. The tongues 88 and 90 are beveled at their ends and the sides 84 have corner flaps 92, foldable inwardly for providing blunt turned edge corners. These flaps may be folded inwardly and secured to the inner faces of the sides 84 before the other parts are assembled, if desired.

The numeral 93 designates a lining or lining blank, foldable upon transverse lines 94, forming sides 95 and an intermediate connecting portion 96, carrying attaching tongues 97, at its

ends. The sides 95 are provided at their ends with transverse attaching tongues 98, foldable upon lines 98', and the sides 95 have their corners cut away, as shown at 99.

5 As shown in Figures 16 and 17, the first step in assembling is to fold the attaching tongues 86' inwardly upon the upper face of the connecting strip 86, and the tongues 97 inwardly upon the lower face of the strip 96. The sides 95 are now 10 arranged over the sides 84 and the folded tongues 86' and 97 are secured together by lines of stitching 100, by a tubular stitching sewing machine. This attaches the lining sides 95 to the main outer sides 84. The transverse attaching tongues 98 now extend over the transverse folding tongues 90, as shown. As more clearly shown in Figure 15', an inner or window side 101 is provided for coaction with each main side 84. This window side has an opening covered by a transparent sheet 102, which is formed of Celluloid or the like, and secured to the same by a line of stitching 103 or other suitable means. Each window side is provided at its outer end with a transverse folding tongue 104, foldable upon a transverse line 105'. The window side 101 is provided with longitudinal folding tongues 105, foldable upon longitudinal lines 106. The longitudinal folding tongues 105 are provided with longitudinal locking tongues 107. The ends of the folding tongues 104 and 105 are beveled and the window side 101 has tapered corner flaps 108, foldable upon the inner face of the side 101, and cemented thereto for providing blunt turned edge corners. These flaps may be folded over and secured to the side 101 before this side is placed in position, if desired.

As clearly shown in Figures 18 and 19, the next step in assembling is to arrange the inner or window sides 101 inverted beneath the main outer sides 84, with the transverse folding tongues 104 projecting outwardly. The tongues 88, 90 and 104 are now arranged in flat superposed relation and are all secured together by transverse lines of stitching 109, spaced from the folding lines 91.

45 The numeral 110 designates a two-layer partition blank or unit, foldable upon a transverse line 111, forming sides 112. One partition unit 110 is used in connection with each main outer side 84.

50 As more clearly shown in Figures 20 and 21, the next step in assembling is to arrange the folded partition units 110 over the lining sides 95 and main outer sides 84, while the window sides 101 remain beneath the main outer sides 84. The next assembling step is to fold the tongues 88 of each main outer side 84 inwardly and pass the same between the marginal portions of the sides 112, as clearly shown in Figures 22 and 23. The inwardly folded tongues 88 are now secured to both sides 112 of the partition unit by means of longitudinal lines of stitching 113, Figures 22 and 23, effected by a tubular stitching machine. These lines of stitching 113 pass through the sides 112 and folded tongues 88 only, and not through the lining side 95, Figure 23. The lines of stitching 113 are spaced inwardly from the outer longitudinal edges of the sides 112, affording marginal edge portions outwardly of the lines of stitching. The lines of stitching 113 are spaced or interrupted at 115, for providing openings or passages, occurring between the sides 112 of the partition unit.

55 As more clearly shown in Figures 24, 25 and 26, the next step in assembling, is to swing each connected window side 101 upwardly upon the several

folding lines 98', 91 and 105', whereby they are arranged over the partition units 110, and the inwardly extending folded tongues 98, 99 and 104 may be inserted between the disconnected ends of the sides 112 of the partition unit.

As more clearly shown in Figures 27 and 28, the next step in assembling is to fold the folding tongues 105 of each window side 101 inwardly to be positioned between the marginal portions of the sides 112 of the partition unit outwardly of the lines of stitching 113 and then pass the locking tongues through the openings or passages 115 in the lines of stitching 113, so that these locking tongues engage behind the lines of stitching 113. This completes the assembling. The several corner flaps may be previously folded in or may be folded in at this point and secured in the folded position. As more clearly shown in Figure 25, the window side 101 forms a pocket 116 with one partition side 112, and the other partition side 112 forms a pocket 117 with the lining side 95 and the main outer side 84. These pockets are open at their inner ends and by virtue of the arrangement of the several folding tongues, extend throughout the entire width and length of their sides, providing the maximum holding capacity. The several inwardly bent folding tongues provide marginal folded edges and a bellows construction at the marginal edges of the device. The lines of stitching 113 prevent the sides 112 of each partition unit from spreading inwardly of such lines of stitching, and also securely attach the main outer sides to the partition unit. The line of stitching 109 securely closes the outer ends of the pockets in each pocket construction.

The several blanks or sides are formed of leather, artificial leather, or any other suitable material.

It is to be understood that the forms of my invention herewith shown and described are to be taken as preferred examples of the same, and that various changes in the shape, size and arrangement of parts may be resorted to without departing from the spirit of my invention or the scope of the subjoined claims.

Having thus described my invention, what I claim is:

1. A folder, comprising main outer sides having marginal folding tongues, partition units arranged opposite the main outer sides, each partition unit including opposed sides, lines of stitching connecting the sides of each partition unit and spaced inwardly from the edges of such sides, inner sides arranged opposite the partition units, each inner side having marginal folding tongues, the folding tongues of the main outer sides being folded inwardly and arranged between the sides of the partition units outwardly of the lines of stitching, the folding tongues of the inner sides being folded inwardly and arranged between the sides of the partition units outwardly of the lines of stitching, means for securing the folding tongues of the main outer sides with the sides of the partition units which are next to the main outer sides and not to the remaining sides of the partition units, and means for securing the folding tongues of the inner sides to the sides of the partition units which are next to such inner sides and not to the remaining sides of the partition unit.

2. A folder, comprising main outer connected sides having longitudinal and transverse folding tongues, partition units arranged opposite the main outer sides, each partition unit including

opposed sides, a U-shaped line of stitching connecting the sides of each partition unit and spaced inwardly from its edges, inner sides arranged opposite the partition units, each inner side having longitudinal and transverse folding tongues, the folding tongues of the main outer sides being folded inwardly and extending between the sides of the partition units outwardly of the line of stitching, the folding tongues of the inner sides being folded inwardly and extending between the sides of the partition units outwardly of the line of stitching, and means to secure the several folding tongues in place said means not connecting the opposed sides of each partition unit outwardly of the U-shaped line of stitching.

3. A pocket construction, comprising a first side provided with marginal folding tongues, a partition unit arranged opposite the first side and including opposed sides, a U-shaped line of stitching connecting the opposed side partition unit and spaced inwardly from the edges of such unit, a second side arranged opposite the partition unit and having marginal folding tongues, the folding tongues of the first side being folded inwardly and extending between the sides of the partition unit outwardly of the line of stitching, means to secure the tongues of the first side to one side of the partition unit outwardly of the line of stitching, the folding tongues of the second side being folded inwardly and arranged between the sides of the partition unit outwardly of the line of stitching, and means separate from the first named securing means to secure the tongues of the second side to the other side of the partition unit outwardly of the line of stitching.

4. A pocket construction, comprising a first side provided with marginal folding tongues, a partition unit arranged opposite the first side and including opposed sides, the marginal tongues of the first side being folded inwardly and arranged between the sides of the partition unit, lines of stitching connecting the tongues of the first side and one side of the partition unit, a second side arranged opposite the partition unit and having marginal folding tongues which are folded inwardly and arranged between the sides of the partition unit and secured to the other side of the partition unit by glue or the like, and lines of stitching connecting the sides of the partition unit and disposed inwardly of the first named lines of stitching.

5. A pocket unit, comprising a first side having marginal folding tongues provided with locking tongues, a partition unit arranged opposite the first side and including opposed sides, lines of stitching connecting the sides of the partition unit, each line of stitching including longitudinally spaced stitching sections passing through the opposed sides and connecting them, the stitching sections forming passages between the opposed sides, a second side arranged opposite the partition unit and having marginal holding tongues provided with locking tongues, the folding tongues of the first side being folded inwardly to pass between the sides of the partition unit and their locking tongues being inserted through the passages to engage behind the lines of stitching, the folding tongues of the second side being folded inwardly and extending between the sides of the partition unit and having their locking tongues pass through the passages for engaging behind the lines of stitching.

6. A folder, comprising connected main outer sides, each main outer side having longitudinal

and transverse marginal folding tongues, a partition unit for each main outer side and including opposed sides, the longitudinal folding tongues of each main outer side being folded inwardly and passed between the longitudinal marginal portions of the sides of the partition unit, lines of stitching including longitudinally spaced stitching sections passing through the longitudinal folding tongues of the main outer side and the sides of the partition unit, the spaced stitching sections forming passages between the sides of the partition unit, an inner side for coaction with each partition unit and having longitudinal folding tongues provided with locking tongues and a transverse folding tongue, means connecting the transverse tongue of each main outer side and the transverse tongue of the inner side, the inner side being arranged over the main outer side and the connected transverse tongues being passed between the outer ends of the sides of each partition unit, the longitudinal folding tongues of the inner side being folded inwardly and inserted between the longitudinal marginal edges of the sides of each partition unit and their locking tongues inserted through the passages between the opposed sides of the partition unit to engage behind such longitudinal lines of stitching.

7. A folder, comprising connected main outer sides, each main outer side having longitudinal marginal folding tongues, a partition unit for each main outer side including opposed sides, the longitudinal folding tongues of each main outer side being folded inwardly and passed between the longitudinal marginal portions of the sides of the partition unit, lines of stitching including longitudinally spaced stitching sections passing through the longitudinal folding tongues of the main outer side and the sides of the partition unit, the spaced stitching sections forming passages between the sides of the partition unit, an inner side for coaction with each partition unit and having longitudinal folding tongues provided with locking tongues, the inner side being arranged over the partition unit and the longitudinal folding tongues of the inner side being folded inwardly and inserted between the marginal edges of the sides of each partition unit and their locking tongues inserted through the passages between the opposed sides of the partition unit to engage behind such longitudinal lines of stitching.

8. A folder, comprising connected main outer sides having transverse end folding tongues, a partition unit disposed opposite each main outer side and including sides having outer ends, an inner side for coaction with each partition unit and having an outer transverse end folding tongue, means connecting the transverse end folding tongue of the main outer side with the transverse end folding tongue of the inner side, the inner side being arranged upon the face of the partition unit remote from the main outer side and the connected transverse tongues being passed between the outer ends of the partition unit, and means connecting the longitudinal edges of the main outer side and the inner side with the partition unit.

9. A folder, comprising connected outer main sides having transverse end folding tongues, a lining comprising sides disposed opposite the outer main sides, the lining sides having transverse end tongues disposed adjacent to the transverse end tongues of the outer main sides, a partition unit for coaction with each lining side and in-

cluding opposed sides, an inner side for coaction with each partition unit having an end tongue, means connecting all of the end tongues in each group, the inner sides being arranged over the partition units and the groups of connected end tongues being arranged between the sides of the partition units, and means for connecting the longitudinal edges of the outer main sides and the inner sides with the partition units.

10. A pocket unit, comprising a side unit including opposed sides, lines of stitching disposed near the opposed edges of the sides, the lines of stitching including longitudinally spaced stitching sections passing through the opposed sides and connecting them, the stitching sections forming passages between the opposed sides, and a side arranged opposite one face of the side unit and provided at its opposed edges with folding tongues provided with locking tongues, the folding tongues being folded inwardly to cover the opposed edges of one side of the side unit and the locking tongues being inserted through the passages between the opposed sides of the side unit and engaging the stitching sections inwardly of such stitching sections.

11. A pocket unit, comprising a partition unit including opposed sides, means connecting the opposed sides of the partition unit and spaced inwardly from the edges of such sides, a first coacting side arranged opposite one face of the partition unit and having marginal folding tongues, a second coacting side arranged opposite the remaining face of the partition unit and having marginal folding tongues, the folding tongues of the first coacting side being foldable inwardly to cover the edges of the adjacent side of the partition unit and arranged between the sides of the partition unit outwardly of the connecting means, the folding tongues of the second coacting side being folded inwardly to cover the edges of the adjacent side of the partition unit and arranged between the sides of the partition unit outwardly of the connecting means, means for securing the folding tongues of the first coacting side with the side of the partition unit which is next to the first coacting side and not to the remaining side of the partition unit, and means for securing the folding tongues of the second coacting side to the side of the partition unit which is next to the second coacting side and not to the remaining side of the partition unit.

12. A pocket unit, comprising a partition unit including opposed sides, lines of stitching disposed near the opposite edges of the sides, the lines of stitching including longitudinally spaced stitching sections passing through the opposed sides and connecting them, the stitching sections forming passages between the opposed sides, a first coacting side arranged opposite one face of the partition unit and provided at its opposite edges with folding tongues provided with locking tongues, the folding tongues being folded inwardly to cover the opposed edges of the adjacent side of the partition unit, the locking tongues being inserted through the passages between the sides of the partition unit and engaging with the stitching sections inwardly of the same, and a second coacting side arranged opposite the remaining face of the partition unit and provided at its opposite edges with folding tongues which are folded inwardly to cover the opposed edges of the adjacent side of the partition unit, and means for securing the last named tongues in place.

13. A pocket unit, comprising a partition unit

11

including opposed sides, a first coating side arranged opposite one face of the partition unit and provided at its opposite edges with folding tongues which are folded inwardly to cover the opposed edges of the adjacent side of the partition unit, lines of stitching disposed near the opposite edges of the sides of the partition unit, the lines of stitching including longitudinally spaced stitching sections passing through the opposed sides of the partition unit and the folding tongues of the first coating side, the stitching sections forming passages between the sides of the partition unit, a second coating side arranged opposite the remaining face of the partition unit and provided at its opposite edges with 15 folding tongues provided with locking tongues, the last named folding tongues being folded inwardly to cover the opposed edges of the ad-

5

jacent side of the partition unit, the locking tongues being inserted through the passages and engaging with the stitching sections at their inner sides.

HENRY M. HERBENER.
